UNITED STATES PATENT OFFICE.

AUGUST STEPHAN, OF FREEPORT, ILLINOIS.

MECHANICAL MEASURE.

1,193,842.

Specification of Letters Patent. Patented Aug. 8, 1916.

Application filed May 20, 1915. Serial No. 29,368.

To all whom it may concern:

Be it known that I, AUGUST STEPHAN, a citizen of the United States, residing at Freeport, in the county of Stephenson and 5 State of Illinois, have invented certain new and useful Improvements in Mechanical Measures; and I do declare the following to be a full, clear, and exact description of the invention, such as will enable others skilled 10 in the art to which it appertains to make and use the same.

My invention is an improved mechanical measuring device for dispensing numerous kinds of fluids, the present embodiment of 15 the invention, however, being designed primarily for measuring heavy oils, but it will be evident that its application need not be limited to use for this one purpose.

The object of the invention is to provide 20 a device of the class described which may be simply and inexpensively manufactured and marketed, yet which when applied to use, will be efficient and durable and will possess a number of advantageous features.

25 With this general object in view, the invention resides in certain novel features of construction and in the unique combinations of parts hereinafter fully described and claimed.

30 In the accompanying drawings which constitute a part of the application, Figures 1 and 2 are vertical sections of the invention showing two different positions of the valve member thereof and parts operable therewith; and Figs. 3 and 4 are horizontal sections as seen on the planes indicated by the 35 lines 3—3 and 4—4 of Fig. 1.

In describing the invention, I shall refer to these drawings by similar reference characters placed on corresponding parts throughout the several views, the numeral 1 indicating an upright tank which may be of rectangular formation as shown in the drawings or of any other preferred design, 45 said tank being provided with a removable cover plate 2 having near its center a stuffing box 3 and an air vent 4, while spaced near one of its edges, the opening 5 is provided, this opening being alined with an additional 50 opening 6 which is formed in the bottom 7 of the tank. In addition to the opening 6, the bottom 7 is provided with a second opening 8 spaced inwardly therefrom and with a third opening 9 spaced an appropriate 55 distance from the opening 8.

Depending through the alined openings 5 and 6 and having nuts 10 bearing against the outer sides of the top and bottom, is the upright feed pipe 11 whose upper end may be connected to any appropriate source of 60 fluid supply, while its lower end is threaded into one end of a U-coupling 12 whose other end receives therein a pipe 13 which constitutes a continuation of the feed pipe and which is passed upwardly through the opening 8 in the bottom 7, while threaded upwardly through the opening 9, is a delivery pipe 14.

As clearly shown in Figs. 1 and 2, the two pipes 13 and 14 rise from the bottom 7 and are threaded into a pair of eccentrically disposed openings in a stationary plate 15, this plate being preferably though not necessarily of circular formation as shown in Fig. 4. By this detail of construction, it 70 will be evident that no other fastening means is necessary to secure the plate 15 (an essential part of the invention) in place, but that the two pipes 13 and 14 effectively accomplish this end.

Overlying the plate 15 and having apertures alined with the pipes 13 and 14 and an additional aperture alined with the socket 16 formed in the upper side of said plate 15, is a washer 17 of leather or the like, while bearing upon the upper side of this washer, is the rotatable valve plate 18 having therein a port 19 adapted to normally aline with the inlet 13 to allow the tank to fill with the oil or other fluid to be 90 dispensed. It is to be observed, however, that when the port 19 is so alined with the pipe 13, an imperforate portion of the plate 18 overlies the open upper end of the pipe 14 and prevents the discharge of fluid therefrom until said plate is rotated a predetermined amount to bring one of an arcuate series of delivery pipes 20 carried thereby and projecting therethrough, into alinement with the pipe 14.

The delivery pipes 20, as clearly shown in Figs. 1 and 2, rise from the plate 18 and are disposed on an arc spaced either radially inward or radially outward from the port 19, whereby regardless of the amount to which the plate 18 is rotated, none of said delivery pipes 20 will register with the inlet pipe 13, but any one of the aforesaid pipes 20 may be brought into vertical alinement with the pipe 14. By so doing, and by vary-

ing the lengths of the pipes 20, any desired quantity of fluid may be discharged from the tank. As illustrative of this manner of operation, let us assume that one pint of oil 5 is to be dispensed from the tank 1, which, due to the normal alinement of the port 19 with the inlet pipe 13, is filled with such oil. The valve plate 18 is rotated by means yet to be described to a predetermined point, 10 thereby bringing the highest pipe 20 into register with the delivery pipe 14, but simultaneously causing the imperforate edge portion of said plate 18 to close the end of the inlet pipe 13, the result being that the oil 15 within the tank will be discharged through the active pipe 20 and the delivery pipe 14, until the level of such oil reaches the upper end of the pipe 20 in question. Needless to say, the supply delivered to the pipe 14 is 20 then checked. The same operation takes place when discharging any desired amount of fluid from the tank, by positioning the proper pipe 20 above the delivery pipe, the relative positions of the pipes 20 and 14 being 25 ascertained from the exterior of the tank by any appropriate type of indicating means placed thereon. Such means, however, is not illustrated since any one of the numerous designs of such devices, well 30 known to those skilled in the art to which the invention relates, may be applied to use for this purpose.

In order to retain the plate 18 in proper relation to the pipes 13 and 14, the center 35 thereof is provided with a journal 21 preferably though not necessarily formed as an integral part thereof, and received by the sprocket 16 while in order to rotate the plate 18 in the manner above set forth, it is 40 provided with an upright cylindrical stem 22 either formed integrally therewith or secured thereto in any preferred manner, the upper end of this stem being extended through the stuffing box 3 and being reduced 45 directly above said box to provide an annular shoulder 23 against which a nut 24 having a threaded engagement with a portion of said stuffing box bears, whereby to retain the plate 18 in proper frictional contact with 50 the washer 17 for obvious reasons. Secured to the upper end of the stem 22, directly above the nut 24, is a handle 25 which may be in the form of a lever as disclosed in the present application, or of any other preferred design.

From the foregoing description, taken in connection with the accompanying drawings, it will be evident that although very simple construction has been provided for the 60 attainment of the desired ends, the complete device will be highly efficient in operation and will possess a number of advantageous features. Particular emphasis is laid upon the unique manner in which the plate 15 is

secured in position, upon the relative positions of the pipes 20 in respect to the pipe 13, whereby they may at no time aline with each other, and upon the general construction of the entire machine.

In the drawings, certain specific details 70 of construction have been shown for accomplishing probably the best results, and in the preceding such details have been described, but it will be evident that I need not be limited thereto, or to character of materials, proportions of parts, etc., otherwise than to the extent to which the appended 75 claims restrict me.

I claim:—

1. In combination, a tank having in its 80 bottom a pair of spaced openings, a non-rotatable plate disposed in contact with said bottom and having openings alined with the aforesaid openings, an inlet pipe threaded through one of the openings in the bottom 85 and into one of the openings in the plate, a delivery pipe threaded through the other opening in the bottom and into the other opening in the plate, a rotatable valve plate operating over the aforesaid plate and having its axis disposed nearer to one of the aforesaid pipes than to the other, a port in said valve plate normally alining with the inlet pipe, and an arcuate series of upstanding delivery tubes of unequal length rising 90 from the valve plate and spaced from the axis thereof a distance equal to that at which the delivery pipe is spaced therefrom.

2. In a fluid measuring device, the combination of a horizontal rotary valve disk 100 having concentric with its axis a series of upstanding fluid delivery tubes of unequal lengths, said disk also having an inlet opening spaced radially from the arc of the series of tubes, in combination with a tank, a fluid inlet into the bottom thereof adapted 105 for registration with the inlet opening in the valve disk, and an outlet from said tank for registration with the aforesaid fluid delivery tubes.

3. A fluid measuring device comprising a closed tank having a flat horizontal bottom, a flat horizontal plate resting on said bottom and having in its upper side a central socket, a flat horizontal gasket resting on the plate 115 and having an opening registering with the socket, an upright inlet pipe threaded through the tank bottom, the plate and into the gasket, an upright outlet pipe likewise threaded through the tank bottom, the plate and into the gasket, said pipes terminating in a plane below the upper side of the gasket and being spaced unequal distances in opposite directions from the socket, a flat horizontal valve plate resting on the gasket 120 and having a central stud depending into said socket, said plate also having a single inlet opening for registration with the inlet 125

pipe, an arcuate series of upright outlet tubes of unequal lengths rising from the valve plate and adapted for registration with the outlet pipe, means for rotating said valve plate, and means for supplying fluid to the aforesaid inlet pipe.

5 In testimony whereof I have hereunto set

my hand in presence of two subscribing witnesses.

GUS STEPHAN.
